JAMES G. BLUNT, OF SCHENECTADY, AND HARRY SWOYER, OF DUNKIRK, NEW YORK.

WATER-GAUGE COLUMN.

1,415,862.

Specification of Letters Patent. Patented May 16, 1922.

Application filed May 26, 1921. Serial No. 472,742.

To all whom it may concern:

Be it known that we, JAMES G. BLUNT, of Schenectady, in the county of Schenectady and State of New York, and HARRY SWOYER, of Dunkirk, in the county of Chautauqua and State of New York, have jointly invented a certain new and useful Improvement in Water-Gauge Columns, of which improvement the following is a specification.

10 Our invention relates to columns for supporting the water glasses and gauge cocks of steam boilers, and its object is to provide an appliance which shall be of simple construction and ample strength to avoid liability to fracture under pressure, and which shall further, afford improved facilities for carrying off the waste water from the gauge cocks and water glasses, without scattering it.

20 The improvement claimed is hereinafter fully set forth.

In the accompanying drawing: Figure 1 is a view, in elevation, of a water column and its accessories, embodying our invention, connected, in operative relation, to a steam boiler; Fig. 2, a partial longitudinal central section, taken at a right angle to Fig. 1; Fig. 3, a horizontal section, on an enlarged scale, on the line *a a* of Fig. 2; Fig. 4, a longitudinal central section, on an enlarged scale; and, Figs. 5 and 6, similar sections, illustrating modifications of structural detail.

30 In the practice of our invention, referring descriptively to the specific embodiment thereof which is herein exemplified, we provide a cylindrical body, 1, which is formed of a straight piece of rolled pipe or tubing, to the ends of which, upper and lower connection castings, 1^a, 1^b, are secured by screw threads. The upper connection casting, 1^a, is connected, by a steam supply pipe, 2, and coupling nuts, 2^a, 2^b, to the shell of a steam boiler, A, at a suitable height 40 above the normal water level therein, and the lower connection casting, 1^b, is connected by a water supply pipe, 3, and coupling nut, 3^a, to the shell of the boiler, at a proper distance below the normal water level.

50 Gauge cocks, 4, in this instance three in number, are connected to the water column, 1, being, as in ordinary practice, spaced at such distances above the crown sheet of the boiler, as to indicate, when opened, the variations of level of the water in the boiler,

and a glass gauge tube, 5, of any preferred type, is secured to the water column by valved end pieces, 5^a.

The several gauge cocks, 4, discharge into a dripper, 6, which is a casting, the upper portion of which is in the form of a plate of segmental section, with its axis coincident with that of the body, 1, and the lower portion is tubular, partly of section, as shown in Fig. 3, and partly of cylindrical section in line axially with the body 1. The dripper is connected, at its lower end, to a discharge pipe, 7, and is adjustably secured to the lower connection casting, 1^b, by a clamping bolt, 6^a, fitting in a circumferential groove or recess, 1^c, in the lower connection casting, and having a nut, 6^b, by which nut, jaws, 6^c, on the dripper, through which jaws the bolt, 6^a, passes, may be drawn tightly together, so as to hold the dripper in any desired and circumferential adjusted position relatively to the axial line of the body.

In the modification of structural detail shown in Fig. 5, the body is swaged down at its ends, and external screw threads are cut thereon, which engage corresponding internal threads on the upper and lower connection castings. The body may, if preferred, be of uniform diameter throughout with external screw threads on its ends, for engagement with the connection castings, as shown in Fig. 6.

It will be seen that the appliance above described, combines lightness with ample strength to guard against fracture by pressure strains, the consequences of which are often disastrous to operators of steam boilers, and that the connection of the gauge cocks and water gauge glass to the column may be readily and securely effected. A further feature of practical advantage is presented in the provision of a dripper which may be circumferentially adjusted and held in any desired position, and is of such construction and capacity as to be capable of carrying off all waste water discharged, without scattering it on the engineer or fireman.

We claim as our invention and desire to secure by Letters Patent:

1. The combination of a water gauge column; upper and lower connection castings, secured to the ends of said body; a plurality of gauge cocks, secured to said body,

intermediate of its ends; and a circumferentially adjustable dripper, connected to the lower connection casting.

2. The combination of a water gauge column; upper and lower connection castings, secured to the ends of said body; a plurality of gauge cocks, secured to said body, intermediate of its ends; a dripper, having projecting jaws, embracing the lower connection casting; a clamping bolt, passing through said jaws and fitting in a circum-

ferential recess in the lower connection casting; and a nut, engaging said clamping bolt and bearing on one of said jaws.

JAMES G. BLUNT.
HARRY SWOYER.
